CLIP

Jesse J. Robbins, Glendale, Calif., assignor to
Stylofede Corporation, Glendale, Calif., a corporation of California

Application September 22, 1945, Serial No. 618,031

9 Claims. (Cl. 24—11)

1

My invention relates to fastening devices and more particularly to clips by which articles may be prevented from falling from pockets and the like. Heretofore, it has been common to provide clips on pencils, pens, combs, files, and the like, by which such articles when slipped into the pocket may be affixed to the edge of such pocket and prevented thereby from falling out. Clips are not always provided on such articles, however, in that where the same are intended for carrying in purses, it is desirable that there be no projections extending from the article that might catch on linings, cloth, keys, matches or other articles in proximity thereto.

The advantages of providing pencils, pens, combs, files and the like with flush clips, which may be extended for attachment purposes, are manifest. Flush clips have been provided in the past as witness by Patent No. 2,010,466, issued to me August 6, 1935, but in general these devices are complex, require numerous parts of expensive construction and are of bulky nature.

It is my object by this invention to provide such a flush clip which may be extendable at will and which is of extremely simple and compact construction, requiring few and inexpensive parts and taking up little room in the article to which it is connected.

A secondary object of my invention is to provide in it such construction that no rotation of parts is necessary. Thus, my invention is not restricted in utility to use in mechanical pens or pencils, which have normally rotating elements, but may be used with any device desired to be attached to the clothing.

A further object of my invention is to provide my clip positively urged either to flush position or to extended position resulting in the clip neither tending to extend accidentally nor slip from clipping position accidentally.

Other objects and advantages of this invention, it is believed, will be apparent from the following detailed description of a preferred embodiment thereof as illustrated in the accompanying drawings.

In the drawings:

Figure 1 is a side view of a pencil incorporating my clip in flush position.

Figure 2 is a side view of a pencil incorporating my clip in its extended position.

Figure 3 is an enlarged top view of said pencil with cap removed, incorporating my invention.

Figure 4 is a cross section taken through my invention on the line 4—4 of Figure 3.

Figure 5 is the same view with my clip partly extended.

2

Figure 6 is the same view showing my clip in flush position.

Figure 7 is a cross section through my invention taken on the line 7—7 of Figure 3 showing my clip in extended position.

Figure 8 shows a cross section taken along the line 8—8 of Figure 3.

Figure 9 is a perspective view of the wire spring used in my invention.

10 Figure 10 shows the stamped sheet metal form which is bent to provide the case for my clip.

Referring to the drawings, Figure 1 shows a mechanical pencil 10 having a disk 12 on which sits my clip mechanism 14. The cap 16 is removable to permit the insertion of the clip mechanism, which is held from rotation in the pencil by the longitudinal grooves 18 in the inner-circumferential surface of the pencil. Indent 20 is formed in the side of said pencil 10 by an accommodation hole 21 through which hole extends the clip 22.

The clip mechanism is of rectangular construction and comprises the case 24, which may be stamped from a flat metal sheet, as shown in Figure 10, and bent to the rectangular shape of said case 24. The clip 22 has at one extremity the flat plate 26, which has studs or integral pintles 28 pivoted in the holes 30 of the case 24. Within the case 24 is positioned the overcenter wire spring 32 shown in perspective in Figure 9. The free end portions 34 of said spring 32 are adapted to abut against the plate 26, tending to press said plate flat against the case 24. The wire spring 32 is held in place on the said case 24 by the crimps 36, and the stops 38.

Thus, in operation it is seen by Figure 6 that in the flush position the wire spring 32 by virtue of its resilient action tends to hold the plate 26 flat against the case 24. When the fingernail is inserted in the indent 20 and the clip 22 pulled outwardly, the position shown in Figure 5 is attained, a point just past which might be called a "dead-center" position. The further pulling of the clip 22, to the position as shown in Figure 4, results in pivoting the plate 26 over said dead-center position until the wire spring 32 tends through its resilient action to further pivot the plate 26 until the clip 22 presses resiliently against the pencil 10, holding said pencil firmly to any cloth or other substance interposed therebetween.

It is apparent that whether the clip be extended or flush, the action of the overcenter wire spring 32 is to maintain such condition by virtue of its tendency to press the plate 26 against the case 24.

Having fully described my invention, it is to

be understood that I do not wish to be limited to the details herein set forth, but my invention is of the full scope of the appended claims.

I claim:

1. A device of the class described comprising: a case including spaced side walls; a plate pivotally mounted in said case between said side walls; a clip forming an extension of said plate and movable between a retracted position within said case, and an extended position beyond an end of said case; and a wire spring in said case abutting said plate and urging said plate to stable positions whereby said clip is urged to remain within said case or to extend from said case.

2. A device of the class described comprising: a case having an end wall and spaced side walls; a plate pivotally mounted in said case adjacent said end wall to move between positions in which the plate lies flatwise against said end wall; a clip forming an extension of said plate and movable between a retracted position within said case, and an extended position overlying said end wall; and a wire spring in said case abutting said plate and urging said plate to a position whereby said clip extends from said case.

3. A device for clipping an article to clothing, comprising: a case, said case having side walls and end wall within said article; a plate pivotally mounted in said case between said side walls and adjacent said end wall; a clip forming an extension of said plate and adapted to extend through said article, there being an accommodation hole therein; and a wire spring in said case urging said plate to a position against said end wall whereby said clip presses resiliently against said article whereby clothing may be held therebetween.

4. A device for clipping an article to clothing, comprising: a case within said article; a plate pivotally mounted within said case; a clip comprising an extension of said plate and adapted to extend through said article, there being an accommodation opening therein; and a wire spring abutting said plate, said plate movable through an edgewise position relative to said spring whereby said spring exerts an over-center force urging said plate toward either of two extreme positions whereby said clip is resiliently restrained within said case or resiliently held in an extended position relative thereto; said clip being shaped to clamp clothing overlying said article.

5. A concealable device for clipping an article to clothing the article having an accommodation hole comprising: a case within said article; an arcuate clip pivotally mounted within said case adaptable for extension through said hole; and overcenter acting resilient means co-acting with the inner end of said clip for resiliently holding said clip in its position within said case and resiliently urging said clip through said hole into overlying relation with said article to press against said clothing interposed between said article and said clip when said clip is extended.

6. A concealable device for clipping an article to clothing, wherein the article has an accom-

modation opening therein, said device comprising: a frame within said article; an arcuate clip pivotally mounted by one end for movement of its other end through said accommodation opening between a concealed position and an extended position; and yieldable means carried by said frame and positioned to apply overcenter pressure on the pivotally mounted end of said clip to hold the extended end thereof yieldably in its concealed position or its extended position.

7. A concealable device for clipping an article to clothing, wherein the article has an accommodation opening therein, said device comprising: a frame of sheet material having spaced side walls and an end wall, and adapted to be secured within an article; an arcuate clip having an extremity pivotally mounted between said side walls and adjacent said end wall to effect movement of the free end of said clip between an extended and a retracted position, said clip being movable through the accommodation opening in said article; and a spring mounted in said frame and engageable with said clip extremity to effect overcenter movement of said clip extremity until stopped by said end wall.

8. A retractable clip for securing articles to clothing, comprising: a frame of sheet material including spaced side walls and an end wall; an arcuate arm having an extremity journaled between said side walls in contiguous relation to said end wall whereby said end wall forms a stop limiting said extremity to approximately a half turn whereby said arcuate arm is movable between an extended position overlying said end wall and a retracted position within said frame; and a spring mounted within said frame and disposed in overcenter bearing relation to said extremity to urge it to either of its extreme positions.

9. A retractable clip for securing articles to clothing, comprising: a frame of sheet material including spaced side walls and an end wall; a spring element having U-shaped arms lying contiguous to said side walls and secured at their ends remote from said end wall, their free ends tending to bear against said end wall; an arcuate arm including an extremity journaled between said side walls and disposed in overcenter bearing relation with said spring element between its arms and said end wall; said arcuate arm positioned to curve from said extremity over said end wall and movable as said extremity is pivoted between an extended position overlying said end wall and a retracted position within said frame.
